UNITED STATES PATENT OFFICE.

ANGUS S. MACDONALD, OF GREAT NECK STATION, NEW YORK, ASSIGNOR TO THE SNEAD & CO. IRON WORKS, OF JERSEY CITY, NEW JERSEY, A CORPORATION OF NEW JERSEY.

DESIGN FOR AN ASH-TRAY.

53,397.

Specification for Design.

Patented June 3, 1919.

Application filed December 4, 1918. Serial No. 265,301. Term of patent 7 years.

To all whom it may concern:

Be it known that I, ANGUS S. MACDONALD, a citizen of the United States, residing at Great Neck Station, in the county of Nassau and State of New York, have invented and produced a new, original, and ornamental Design for an Ash-Tray, reference being had to the accompanying drawings, which form a part of this specification.

My invention relates to an original design for ash trays and resides in the shape or form of the same being novel in its contour and in the arrangement of its ornamentation, as is clearly shown and fully illus-

trated in the annexed drawing, and wherein:—

Figure 1 is a perspective view of the ash tray embodying my new and original design; and Fig. 2 is a fragmentary view drawn on an enlarged scale illustrating the ornamentation in the groove at the upper part of the tray.

What I claim is:

The design for an ash tray substantially as herein shown.

In testimony whereof I have hereunto signed my name and affixed my signature.

ANGUS S. MACDONALD.
